MAGNETIC CONTACT

Anthony H. Lamb, Hillside, N. J., assignor to
Weston Electrical Instrument Corporation,
Newark, N. J., a corporation of New Jersey

Application April 26, 1943, Serial No. 484,611

5 Claims. (Cl. 200—166)

This invention relates to magnetic contacts for use in sensitive instrument type relays, and particularly to a permanent magnet contact assembly including a pair of spaced pole pieces of opposite polarity for simultaneous, or substantially simultaneous, engagement by a magnetic material rider on the contact arm of the relay.

Relay contact systems of this general type are described and claimed in my prior Patent No. 2,193,731, March 12, 1940, "Relay contact." The double contacts may be electrically connected, or they may be insulated from each other, as illustrated in the patent. The contact elements described in the prior patent were miniature bar magnets of material of high coercive force, and the excessive hardness of such materials presented some difficulties in the machining and assembly of the twin contacts.

Objects of the present invention are to provide magnetic contact assemblies for use in sensitive relays, the assemblies comprising small permanent magnets and associated pole pieces of a softer magnetic material that constitute the contact surfaces for engagement with a cooperating magnetic material contact on the relay contact arm. An object is to provide a magnetized twin contact assembly of economical construction for use in relays, the assembly comprising a permanent magnet of plate or miniature bar form and associated contact polar extension of iron or other relatively soft material of high permeability.

These and other objects and the advantages of the invention will be apparent from the following specification when taken with the accompanying drawing in which:

Fig. 1 is a schematic fragmentary view, in perspective and on an enlarged scale, of an instrument type relay including a magnetic contact assembly embodying the invention;

Fig. 2 is a plan view of the relay contacts;

Fig. 3 is a vertical section as taken on line 3—3 of Fig. 2;

Figs. 4, 5 and 6 are, respectively fragmentary perspective, plan and vertical section views of another form of relay contact construction;

Fig. 7 is a side elevation of a modified form of a contact assembly such as shown in Fig. 3; and

Fig. 8 is an enlarged sectional view of a contact assembly in which the polar extensions are insulated from each other.

In Fig. 1 of the drawing, the reference numeral 1 identifies the coil element of a relay moving system that includes a pointer 2 carrying a small cylindrical rider 3 of soft iron or other magnetic

material. The cooperating, relatively stationary contact surfaces are the rounded ends of small pins 4, 5 of soft iron or the like that extend at right angles to and are the pole pieces of a small permanent magnet 6 of block or miniature bar form. The contact assembly is carried by a bracket 7, of brass or other non-magnetic material, that is secured to the scale plate 8 by screws 9. The pole pieces 4, 5 are threaded into the flanged end of bracket 7, and the magnet 6 is secured to the inner face of the end flange by cement or solder 10.

The controlled or relay circuit includes a current source 11 and load 12 connected between the relay pointer 2 and the bracket 7. The polar extensions 4, 5 may be of different length, as explained in my prior patent, to limit the arcing at contact separation to the longer polar extension 4.

The main axis of the permanent magnet 6 may be arranged parallel to the scale plate 8 by turning the end of pointer 2 upwardly at right angles to locate the axis of the soft iron contact 3 in the plane of symmetry between the polar extensions 4, 5. This construction, as illustrated in Figs. 4-6, locates both soft iron contacts 4, 5 at the same distance from the main instrument magnet, not shown, and the contacts therefore are equally affected by the leakage flux of the main magnet. The construction of this contact assembly is similar to that previously described except that, as shown in Fig. 6, the contacts 4, 5 are not threaded into the bracket 7. The contacts may be secured in the bracket by a force-fit or by swaging, or they may be cemented or soldered to the bracket. Cement or solder 10 secures the magnet 6 to the bracket 7 and against the ends of the soft iron contacts 4, 5.

It is also practical to solder or cement the contacts 4, 5 directly to the magnet 6, as shown in Fig. 7, and to solder or cement this contact assembly to the outer face of the bracket 7.

One or both of the iron contacts may be insulated from the magnet 6 and bracket 7, by a thin disk 13 of insulation at the base of the contact and a bushing 14 of insulation. Circuit connections may be made to the contacts 4, 5 by soldering leads 15 directly to them.

The magnetic contact assemblies are to be employed in sensitive instrument type relays, such as described in the prior patent, in which some form of pusher arm or electrical resetting system is provided to overcome the magnetic attraction of the engaged contacts. The magnet may be of small size when materials of high coercive force, such as "Alnico," are employed and, in one satis-

factory construction, the magnet was approximately $0.060 \times 0.080 \times 0.160$ inch. The miniature bar magnets may be manufactured economically as they are merely small blocks that may be cast, pressed from powdered metals or cut from the bar stock and, if necessary or desired, may be readily ground to the required shape and size.

The small size of the contemplated contact assemblies indicates the difficulties previously encountered in shaping and mounting two magnets of exceedingly hard metal. The soft iron contact elements of this invention may be readily formed to desired shape and size by any of the simpler metal working processes, and they can be accurately mounted upon the bracket or directly upon the magnet by economical assembly processes.

It is to be understood that the invention is not limited to the particular constructions herein shown and described, and that there is considerable latitude in the design and construction of the contact assembly within the scope of the invention as set forth in the following claims.

I claim:

1. A twin contact assembly for use in a sensitive instrument relay of the magnetic contact type; said assembly comprising a miniature bar magnet, and pole pieces of soft iron extending in parallel relation from the opposite ends of the bar magnet, and means including a bracket having an end flange supporting said magnet and pole pieces in fixed assembled relation, said magnet being attached to a face of said flange by a binder.

2. A twin contact assembly comprising a supporting bracket of non-magnetic material, twin contacts of magnetic material of low retentivity secured to said bracket, said contacts being of pin form and extending substantially through said bracket from one face thereof, and a miniature bar magnet secured to the opposite face of said bracket with its poles adjacent the inner ends of the respective twin contacts.

3. A twin contact assembly of the magnetic type comprising a bracket of non-magnetic material, a miniature bar magnet secured to said bracket, and contact members of pin form constituting polar extensions of the magnet, said contact members being individually secured to and supported by said bracket.

4. A twin contact assembly for use in a sensitive instrument relay of the magnetic contact type; said assembly comprising a miniature bar magnet, and pole pieces of soft iron extending in parallel relation from the opposite ends of the bar magnet and having outer ends for cooperation with a movable contact of soft iron, a bracket and means securing said magnet to one face of the bracket, said pole pieces extending into the bracket from the opposite face thereof and being rigidly attached to said bracket.

5. A twin contact assembly as recited in claim 4, in combination with means insulating one of said pole pieces from said bracket and said magnet.
